Inventor:

Heinrich Waether

UNITED STATES PATENT OFFICE.

HEINRICH WALther, OF FRANKFORT-ON-THE-MAIN, GERMANY.

MACHINE FOR ATTACHING SOLES TO LASTED SHOES.

Application filed May 2, 1928, Serial No. 274,542, and in Germany July 13, 1926.

This invention has reference to improvements in machines for attaching soles to lasted shoes, and more particularly to machines whereby the contacting surfaces of the soles 5 and of the lasted shoes having previously been coated with an adhesive are firmly pressed together and the pressure maintained for a sufficient time to allow the cement to set. The machines of this kind consist mostly of a series of pressure devices arranged on a rotatable carrier each device being adapted to work upon a separate shoe. These pressure devices consist of flexible cushions onto which the shoes operated upon are held or pressed by 10 bridge-like levers.

The object of the present invention is to simplify the machine referred to and to improve its operation.

According to an important feature of the 20 invention the cushions and the pressing levers are pivoted or linked to each other so as to close like scissors and to grasp the sole and the lasted shoe to be connected to each other at first at one end, preferably at the toe of the 25 shoe. By this means the pressure exerted upon the parts to be united propagates from one end, preferably from the toe of the shoe to the other end, thus preventing a displacing of the sole with relation to the lasted shoe. 30 Thereupon the cushion is additionally pressed again the shoe in order to fully conform the sole to the shank of the lasted shoe.

Other features of the invention and details of construction will be apparent from the following description and the accompanying drawings, in which

Fig. 1 is a longitudinal section of a part of the machine;

Fig. 2 is a partial front view of the machine;

Fig. 3 is a view of the bracket 5 with certain parts cooperating therewith as seen from the front and

Fig. 4 is a cross-section of the cushion along 45 the line A—B of Fig. 1.

The shaft 1 is rotatable in the journals 2 and 3 of the brackets 4 and 5 relatively. These two brackets form a rigid machine-frame which may be fastened to the floor in any 50 convenient manner. To the shaft 1 is fastened a plurality of arms 14. Every arm 14 carries a separate pressure device adapted to work upon a shoe. As all pressure devices are of equal construction, I shall describe one de- 55 vice only.

To the arm 14 are screwed the brackets 15.

and 16. To the bracket 16 is pivoted at 50 the two-armed lever 9. This lever carries at its front-end the bridge-piece 22 resting in the working position with its pressing feet 23, 60 23' upon the shoe 51 in the manner illustrated in the drawing. The rear-end of the lever 9 is adapted to abut with its spherical surface 24 upon the adjusting screw 20 of the slide 13 guided in the bracket 16 and held in the shown 65 upper position by the elbow-lever 17 the teeth 21 of which are pressed into engagement with the teeth 21' of the slide 13 by the bolt 19 and the spring 18. The rear-end of the lever 9 is further connected by the link 40 to 70 the container 8 of the cushion 41. The container 8 is itself a lever held down at the left end upon the spring 43 by the nut 44' of the bolt 44. The bolt 44 is screwed into the slide 12 held in its upper position in a similar man- 75 ner as the slide 13 by an elbow-lever 17'. The hand-wheel 45 may be rotated upon the bolt 44 in order to adjust the compression of the spring 43. The lever 9 and the container 8 are kept apart by the spring 25 but they may 80 be made to approach each other by the raising of slide 13. While the lever 9 is lowered with the operating bridge-piece 22 the container 8 is raised by the link 40, the left end of the container resting upon the spring 43. By this 85 means the parts of the shoe to be united are at first taken hold of at the toe of the shoe. When the slide 13 is fully raised the sole is 90 pressed on its entire length against the shoe. Thereupon the slide 12 is carried upwards in 90 order to apply an additional pressure on the shoe. As the stroke of the container 8 at the heel part of the shoe is longer than the stroke at the toe part of the shoe, the movement of the slide 12 will effect an additional pres- 95 sure chiefly at the shank of the shoe just where it is very difficult to conform the sole to the curvature of the lasted shoe.

Of course the cushion 41 consists of a rubber or like bag filled with a fluid or a yielding material. The cushion 41 is protected by an elastic cover 42 having a thick edge 42' accommodated in a corresponding groove of the container 8 and held fast in the groove by the cushion. The cover 42 thus prevents the 100 cushion from extruding from the container when the shoe is pressed therein and allows the free edge of the sole to remain flat while without the said cover the edge would turn upwards.

Having now described one pressure device, 110 I will yet mention that the slides 12 and 13

have rollers 10 and 11 relatively by means of which they are moved upwardly in the following manner.

To the bracket 5 there is fastened a plate 7 the upper rim of which forms a curved path for the roller 11 of the succeeding pressure devices. In the plate 7 is guided a slide 34 adapted to be moved upwards from a treadle not shown by means of the bar 32 and the lever 33 pivoted to the bracket 5 at 52.

When the roller 11 of the pressure-device shown enters the notch 7' of the plate 7, the slide 13 is in its low position so that the spring 25 swings the bridge-piece 22 with the lever 9 upwards to allow a shoe 51 to be placed upon the cover 42 of the cushion 41. Now the treadle not shown is depressed to lift the slide 34, the roller 11 and the slide 13. Thereby the lever 9 and the bridge-piece 22 are lowered to press the shoe onto the cushion 41. The lever 9 while being lowered lifts the container 8 so that the lever 9 and the container 8 move both at the same time against each other like scissor-blades in order to first grasp the lasted shoe and the sole at the toe and then compress these two parts on their whole length. The slide 13 is locked in its upper position by the lever 17 in the manner already described.

The shaft 1 may now be rotated either by hand or by any motive power in the direction indicated by the arrow in Figs. 2 and 3. If the roller 11 has not been lifted by the treadle as to be clear of the cam 7'' of the plate 7 the slide 13 is additionally lifted by that cam 35 when the roller comes into position 11'.

To the bracket 4 is likewise fastened a cam-plate 6 for acting upon the roller 10 and the slide 12. While the roller 11 is in the position shown in Fig. 3 in full lines, the roller 10 rests upon the rim of the plate 6 within the notch 6'. When the shaft 1 rotates the roller 10 rides over the cam 6'' and effects by means of the slide 12 and the spring 43 an additional yielding pressure upon the left end of the container 8. The slide 12 is locked in its upper position by an elbow lever 17' similar in its construction and operation to the lever 17 and needs therefore no further description.

The slides 12, 13 remain locked and the shoe remains under pressure when the rollers 10, 11 leave the cam-plates 6 and 7 relatively until the shaft 1 makes almost a whole revolution and the said rollers come into contact with the cams 6''' and 7'''. These cams are a little higher than the cams 6'' and 7'' and are intended to slightly lift the slides 12, 13, in order to allow the elbow levers 17', 17 to be swung out of engagement with the said slides by the cams 35', 35 on the plates 6 and 7. The slides being unlocked assume again their lower position as soon as their rollers 10 and 11 come into the notches 6' and 7' relatively. Now the spring 25 lifts the front end of the lever 9 at the same time lowering by means of the link 40 the container 8, thus allowing the

shoe with the adhering sole to be removed from the machine.

As the machine has several arms 14 it makes a step by step rotation, so that all pressure devices are successively brought into the 70 positions for removal of the finished shoe and for introducing a fresh shoe.

I claim:

1. In a machine for attaching soles to lasted shoes by means of an adhesive, a flexible 75 cushion acting on the sole, a lever pressing on the lasted shoe and cooperating with the cushion to bring the shoe and the sole into intimate contact, a cushion-carrier, and means for moving the pressing lever and the 80 cushion-carrier simultaneously against each other.

2. In a machine for attaching soles to lasted shoes by means of an adhesive, a flexible cushion acting on the sole, a lever pressing on 85 the lasted shoe and cooperating with the cushion to bring the shoe and the sole into intimate contact, a cushion-carrier, means for moving the lever against the cushion, and a connection between the lever and the cushion-carrier, so that the pressing lever and the 90 said carrier move simultaneously against each other.

3. In a machine for attaching soles to lasted shoes by means of an adhesive, a flexible 95 cushion acting on the sole, a pressure-foot acting on the rear-part of the shoe, a pressure-foot acting on the fore-part of the shoe, a lever carrying the pressure-feet and cooperating with the cushion to bring the shoe 100 and the sole into intimate contact, a cushion-carrier, a pivot-journal of the lever on the side of the pressure foot acting on the fore part of the shoe, means for moving the lever with the pressure-feet, and a pivot-connection 105 between the lever and the cushion-carrier, so that the lever and the cushion-carrier move like shear-blades against each other.

4. In a machine for attaching soles to lasted shoes by means of an adhesive, a flexible 110 cushion acting on the sole, a pressure-foot acting on the rear-part of the shoe, a pressure foot acting on the fore-part of the shoe, a lever carrying the pressure-feet and cooperating with the cushion to bring the shoe and 115 the sole into intimate contact, a cushion-carrier, a pivot-journal of the lever on the side of the pressure foot acting on the fore part of the shoe, means for moving the lever with the pressure-feet, a pivot-connection between 120 the lever and the cushion on the same side of and farther apart from the pressure foot acting on the fore part of the shoe than the said pivot-journal, and separate means for additionally moving the cushion-carrier arranged 125 on the side of the pressure-foot acting on the rear part of the shoe.

5. In a machine for attaching soles to lasted shoes by means of an adhesive, a rotatable carrier, a plurality of devices for pressing 130

- soles to lasted shoes arranged on the rotatable carrier, each device consisting of a container, a flexible cushion accommodated within the container, and a lever pressing the shoe 5 against the cushion, and stationary means for successively pressing each lever and the associated cushion-carrier against each other.
6. In a machine for attaching soles to lasted shoes by means of an adhesive, a rotatable carrier, a plurality of devices for pressing soles to lasted shoes arranged on the rotatable carrier, each device consisting of a container, a flexible cushion accommodated within the container, and a lever pressing the shoe 10 against the cushion, stationary means for successively pressing each lever and the associated cushion-carrier against each other, means on the rotatable carrier for locking the
- lever and the cushion-carrier in the pressing position, and stationary means for successively releasing the locking means of the single pressing devices. 20
7. In a machine for attaching soles to lasted shoes by means of an adhesive, a rotatable carrier, a plurality of devices for pressing soles to lasted shoes arranged on the rotatable carrier, each device consisting of a container, a flexible cushion accommodated within the container, and a lever pressing the shoe 25 against the cushion, foot operated means and means operated by the rotation of the device carrier for successively pressing each lever and the associated cushion-carrier against each other. 30

In testimony whereof I affix my signature.
HEINRICH WALTHER.
